ACTUATING MEANS FOR TWIN MASTER CYLINDERS

Steve Schnell, Kirkwood, Mo., assignor to Wagner Electric Corporation, St. Louis, Mo., a corporation of Delaware

Application October 25, 1941, Serial No. 416,430

9 Claims. (Cl. 74—110)

My invention relates to master cylinder devices employed in fluid pressure actuated systems and more particularly to actuating means for moving the pistons of twin master cylinders.

One of the objects of my invention is to provide improved actuating means which will insure that equal forces will be applied to the pistons or like members of the two master cylinder devices.

Another object of my invention is to so construct an actuating means of the kind referred to that it will be a unitary assembly, completely sealed for lubrication purposes, economically constructed, and efficient in operation.

Other objects of my invention will become apparent from the following description taken in connection with the accompanying drawing in which Figure 1 is a partial sectional view showing an actuating means for two master cylinder devices in which my invention is embodied; and Figure 2 is a sectional view of a modified construction.

Referring to Figure 1 in detail, 1 indicates the twin master cylinders in which is embodied parallel cylinders 2 and 3 having mounted therein for reciprocable movement the pistons 4 and 5. These pistons are adapted to compress fluid in the cylinders and force it out through the outlet conduits 6 and 7 which lead to the fluid motors of different actuating systems such as, for example, brake operating fluid motors. The pistons are shown in their retracted positions determined by the stop plate 8 at the rear end of the cylinders. It is desirable that these pistons, which are of equal size, develop equal fluid pressures when force is applied by means of a single member such as the brake pedal 9.

The connecting means between the pedal 9 (shown in section) and the two pistons whereby equal forces are applied comprises a housing member 10 having parallel bores 11 and 12 connected by a cross-bore 13. This housing member is adjustably connected to the brake pedal by a connecting means comprising a rod 14 threaded into an integral extension 15 projecting rearwardly from the central part of the housing 10. A nut 16 clamps the rod and extension together. The other end of the rod is pivoted on the pin 17 carried by the brake pedal 9.

Associated with the housing member 10 are two sleeves 18 and 19, the sleeve 18 having its rear end press-fitted into bore 12 of the housing and the sleeve 19 having its rear end press-fitted into bore 11 of the housing. The inside of the end of

sleeve 18 which is positioned in the bore is provided with a slot 20. Also, the inside of the end of sleeve 19 which is positioned in the bore 11 is provided with a slot 21.

Within the housing is an equalizing bar 22 having a central spherical portion 23 of a diameter substantially the same as the diameter of the cross-bore 13 and positioned in said cross-bore. The end portions 24 and 25 of the bar 22 which lie in the ends of sleeves 18 and 19 are of flat formation and extend through slots 20 and 21. The edges of these flat end portions are curved as shown. The forward edge of end 24 is adapted to abut the end of a piston rod 26 slidably received in sleeve 18 and of such length as to project beyond the forward end of said sleeve and into the socket 27 in the rear end of piston 4. Similarly, the forward edge of the flat end 25 of the bar is adapted to abut the end of a piston rod 28 slidably received in the sleeve 19 and of such length as to project beyond the end of the sleeve and into the socket 29 of piston 5. A dust boot 30 surrounds the two sleeves and is attached at one end to the sleeves and at the other end to the rear end of the two cylinders to thus totally enclose the piston rods, sleeves, and the rear end of said cylinders.

In making the housing member 10, cross-bore 13 is formed by boring completely through the housing, thus forming the end openings 31 and 32. These openings permit the equalizing bar to be placed in its operative position so that the spherical central portion is in the cross-bore 13. After this bar is in position, sleeves 18 and 19 are then press-fitted into their bores 12 and 11, respectively. Since slots 20 and 21 in the sleeves are on the inner side of said sleeves, the ends of the sleeves will close the openings 31 and 32 when inserted in the bore. Thus, it is seen that the portion of the housing within which the equalizing bar is placed, is totally enclosed. This permits the space around the equalizing bar to be filled with lubricant so as to give proper lubrication to the equalizing bar throughout the life of the structure. It is also to be noted that the whole assembly, including the casing, equalizing bar, sleeves, and piston rods form a single unit after assembly, which unit can be quickly placed in operative position by merely attaching the casing to rod 14 and placing the piston rods in the sockets of the pistons. The dust boot is attached to the unit before the piston rods are placed in the piston sockets.

The equalizing bar has a predetermined

amount of free pivotal movement in the same place as that in which the piston rods lie. When pressure is applied to rod 14 by the brake pedal, it will be transferred by the equalizing bar to the piston rods and pistons to thus cause the pistons to be moved with equal force. If one of the fluid pressure systems served by one of the master cylinders should develop a leak so that it is no longer effective, the other master cylinder can continue to be operated with very little lost motion. For example, if line 6 should break, this will result in the equalizing bar having a clockwise rotation until the rear side of the end 25 thereof engages the housing. When this occurs, there will be a solid connection between rod 14 and piston rod 28 and then all the force applied by the pedal will be applied to piston 5 to develop pressure. Thus it is seen that the only lost pedal travel, when one master cylinder is inoperative, is that determined by the distance between the rear edge of end 25 and the housing which is quite small but, nevertheless, sufficient to allow for the equalizing bar to have sufficient pivotal movement to perform its equalizing action when both pistons are developing fluid pressure.

In Figure 2 there is shown a slightly modified structure. The housing 10' is provided with a cross-bore 33 which extends completely across the housing. The sleeves 18' and 19' only extend into their bores 12' and 11' as far as the juncture thereof with the cross-bore 33. The equalizing bar 22' which is positioned within the bore 33 is provided with a spherical central portion 34 and also with spherical end portions 35 and 36. The extension 15' to which the rod 14 is connected, carries a threaded plug 37 which has an end portion extending into cross-bore 33, which end portion is provided with a concave surface 38 upon which bears the spherical central portion 34 of the equalizing bars. Also, the rear ends of piston rods 26' and 28' are provided, respectively, with concave end surfaces 39 and 40 for engagement with spherical ends 35 and 36 of the equalizing bar. In order that bore 33 may be sealed after the equalizing bar is placed therein and thus provide a chamber to hold a supply of lubricant, the ends of said bore are closed by discs 41 and 42.

The operation of this modification is the same as the structure shown in Figure 1. However, by employing plug 37 with the concave bearing surface 38, there is provided a greater bearing surface through which force may be transmitted. Since the plug is adjustable, any wear can be taken up. Also, by having the ends of equalizing bars 35 and 36 spherically shaped and the cooperating end surfaces of the piston rods provided with concave surfaces, a greater bearing surface is present between the equalizing bar and the piston rods.

Being aware of the possibility of modifications in the particular structure herein described without departing from the fundamental principles of my invention, I do not intend that its scope be limited except as set forth by the appended claims.

Having fully described my invention, what I claim as new and desire to secure by Letters Patent of the United States is:

1. In apparatus of the class described, two pressure producing devices each comprising a movable piston, a housing member having a chamber, an equalizing bar mounted for limited pivotal movement in the chamber of said housing member, guide sleeves carried by said housing 75

member, a piston rod in each sleeve, one of said piston rods having one end engaging one of said pistons and its other end extending into said housing chamber for engagement with one end

5 of the equalizing bar, the other of said piston rods having one end engaging the other of said pistons and its other end extending into said housing chamber for engaging the other end of said equalizing bar, and means connected to the

10 housing for moving said housing so as to transmit equal forces to the piston rods by means of said equalizing bar, said housing, sleeves and rods being so constructed and associated with each other as to totally enclose the equalizing bar.

15 2. In actuating apparatus of the class described for moving two members simultaneously with equal forces, a housing member having a chamber, an equalizing bar mounted for limited pivotal movement in the chamber of said housing mem-

20 ber, parallel piston rods one of which has an end extending into said chamber for engagement by one end of said equalizing bar and the other of which has an end extending into said chamber for engagement by the other end of the

25 equalizing bar, the other ends of said piston rods being adapted for engagement with the two members to be moved, means for so closing said chamber as to permit lubricant to be retained therein, and means connected to the housing for

30 moving said housing so as to transmit equal forces to the rods by means of said equalizing bar.

35 3. In actuating apparatus of the class described for moving two members simultaneously with equal forces, a housing member provided with a chamber, an equalizing bar mounted in said chamber for limited pivotal movement, parallel

40 guide sleeves each having one of its ends carried by said housing member and opening into the chamber adjacent an end of the equalizing bar, a rod slidably mounted in each sleeve, one of said rods having one end engaged by one end of the bar and its other end engaging one of the two members to be moved and the other rod having

45 one end engaged by the other end of the bar and its other end engaging the other of the two members to be moved, and an actuating member connected to apply a moving force to the housing member on the side opposite the rods and sleeves.

50 4. In actuating apparatus of the class described for moving two members simultaneously with equal forces, a housing member provided with a bore open at both ends, an equalizing bar mounted in said bore for limited pivotal movement, par-

55 allel guide sleeves positioned at right angles to the axis of the bore and each having one of its ends carried by said housing member, and opening into the bore adjacent an end of the equalizing bar, a rod slidably mounted in each sleeve,

60 one of said rods having one end engaged by one end of the bar and its other end engaging one of the two members to be moved and the other rod having

65 one end engaged by the other end of the bar and its other end engaging the other of the two members to be moved, means for closing the ends of the bore to thereby enclose the equalizing bar and establish a lubricant chamber, and an actuating member connected to apply a moving force to the housing member on the side opposite the rods and sleeves.

5. In actuating apparatus of the class described for moving two members simultaneously with equal forces, a housing member provided with a cross-bore open at both ends and two parallel bores entering the cross-bore at right angles to

its axis end at opposite ends thereof, an equalizing bar mounted in said bore for limited pivotal movement, two guide sleeves each having one of its ends extending into one of said parallel bores and carrying a portion for closing the adjacent end of the cross-bore, a rod slidably mounted in each sleeve, each of said rods having an end engaged by an end of the bar and its other end engaging one of said two members to be moved, and an actuating member connected to apply a moving force to the housing member on the side opposite the rods and sleeves.

6. In actuating apparatus of the class described for moving two members simultaneously with equal forces, a member provided with a bore, an equalizing bar positioned in the bore and having a central portion provided with an annular curved surface adapted for abutment with a surface carried on the housing and permitting limited pivotal movement relative to the housing, two rods each having one end extending into an end of the bore at right angles to its axis for engagement by an end of the bar, the other end of the rod having engagement with the members to be moved, guide means for each rod carried by the housing, and means for moving the housing and by means of the bar applying equal forces through the rods to the two members.

7. In actuating apparatus of the class described for moving two members simultaneously with equal forces, a housing member provided with a chamber, an equalizing bar positioned in said chamber and having a central spherical portion and spherical end portions, means on the housing for providing a concave abutment surface for cooperation with the central spherical surface of the bar, two rods each having an end extending into an end of the chamber adjacent an end of the bar, each of said rods being provided with a concave surface for cooperation with the spherical surface on the adjacent end of the bar, and means for moving the

housing and by means of the bar applying equal forces through the rods to the two members.

8. In actuating apparatus for twin master cylinders having parallel cylinders and pistons reciprocal therein, a housing member provided with a bore open at both ends, an equalizing bar mounted in said bore for limited pivotal movement, parallel guide sleeves positioned at right angles to the axis of the bore and each having one of its ends secured to said housing member and opening into the bore adjacent an end of the equalizing bar, a piston rod slidably mounted in each sleeve, one of said rods having one end engaged by one end of the bar and the other end abutting one of the two pistons and the other rod having one end engaged by the one end of the bar and its other end abutting the other piston, means for closing the ends of the bore to thereby enclose the equalizing bar and establish a lubricant chamber, a dust excluding boot surrounding the sleeves and rods and having one end attached for movement with the housing and its other end attached to the end of the cylinders, and an actuating rod connected to the housing member on the side opposite the rods and sleeves.

9. A movable connecting means for interposition as an assembled unit between an actuating member and two members to be actuated, said connecting means comprising a housing member provided with a chamber, an equalizing bar mounted in the chamber for limited pivotal movement, parallel guide sleeves carried by the housing and extending from one side thereof, a rod in each guide sleeve, one end of each rod extending into the chamber for engagement with an end of the equalizing bar and having its other end adapted for connection with one of the two members to be actuated, and a rod secured to the housing on the side opposite the sleeve and adapted for connection with the actuating member.

STEVE SCHNELL.
